CARPET.

No. 20,316.

Patented Nov. 18, 1890.

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 20,316, dated November 18, 1890.

Application filed October 20, 1890. Serial No. 368,748. Term of patent 3½ years.

To all whom it may concern:

Be it known that I, HENRY HUNT, of Greenville, county of Hudson, and State of New Jersey, have invented a new and original Design 5 for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet showing my new design.

My design consists of the body A and border B. The body A consists of ornamented scroll-work intertwined with leaf forms. The border B consists of a festooned marginal ornamentation and of ornamental scroll-work 20 intertwined with leaf forms and of the distinct band ornamented with fan and gem forms and serrated as to its outer margin.

What I claim is—

1. A design for carpets, consisting of the 25 body A, substantially as shown.
2. A design for carpets, consisting of the border B, substantially as shown.
3. A design for carpets, consisting of the body A and border B, substantially as shown. 30

HENRY HUNT.
